United States Patent Office.

MARTIN MEYERS, JR., OF PHILADELPHIA, PENNSYLVANIA.

Letters Patent No. 78,308, dated May 26, 1868.

IMPROVED REFRIGERATOR.

The Schedule referred to in these Letters Patent and making part of the same.

TO ALL WHOM IT MAY CONCERN:

Be it known that I, MARTIN MEYERS, Jr., of the city and county of Philadelphia, and State of Pennsylvania, have invented new and useful improvements in Refrigerators; and I do hereby declare the following to be a clear and exact description of the same, sufficient to enable others skilled in the art to which my invention appertains to fully understand and use the same, reference being had to the accompanying drawings; making part of this specification, and in which—

Figure 1 is a plan view of a refrigerator, illustrating my invention, the top being removed.

Figure 2 is a transverse vertical section thereof.

Figure 3 is a front view thereof.

Similar letters of reference indicate corresponding parts in the several figures.

My invention is an improvement in refrigerators, adapted for receiving and cooling milk, butter, meat, and other articles of food, and consists in so constructing the shelves on which the articles rest as to form sliding drawers; having swinging doors, whereby access is readily had to the articles, as well as to all parts of the refrigerator, thus dispensing with the swinging top or cover, and producing an air-tight receptacle in a cheap and simple manner.

My invention further consists in means for properly ventilating the interior of the receptacle, so that the cold air is brought directly against the food on the shelves, and then passed out into the atmosphere, without again coming in contact with said food.

In the drawings, A represents the case of a refrigerator, consisting of an immovable top, the usual front, back, and side pieces, and bottom, and with the cold-air spaces, a, between the inner and outer walls of the case.

B represents the shelves, which consist of drawers or boxes, having their bottoms constructed of gratings or net-work, and are adapted to slide, horizontally, freely in and out of the case, while resting on suitable cleats or strips secured to the inner faces of the case.

The front piece, C, of each drawer-shelf is hinged, so as to swing downwards and outwards, and should be of a size a little larger than the rest of the drawer, so that the joint at the front side of the case will be entirely covered when the drawer or shelf is entirely pushed into the case. The piece C thus forms a lid or door, and is provided with suitable locks, or other fastening-devices, and with knobs or handles, in order to facilitate the operation of handling the said piece.

In order to support the doors when opened, and also to limit their play, I attach brackets, b, to the inner face of the doors, which brackets are slotted, and are guided by pins placed on the inner sides of drawer. These brackets may either be segmental or in the form of an ordinary link.

The back and bottom of each drawer are secured to the side pieces thereof, at a point between the ends and middle, so that when the drawer is entirely in the case, a space, D, is left between the inner back wall and the back of the drawer. Any number of drawers can be employed, and a series of shelves, e, may be secured within them, so as to increase the means for holding various articles.

A space, E, is also allowed between the bottom of the case A and the lowest drawer, which space communicates with space D, which has been described.

A portion of the upper drawer will be formed into an ice-chamber, F, which consists of a suitable metallic case, having a removable bottom, to which is connected a short pipe, d, extending downwards, and having its lower end formed to connect with a vertical pipe, e, secured to the inner wall of the case, and extending downwards below the bottom thereof. The object of these pipes is to conduct the water from the melted ice to a place of deposit or discharge.

A rack or grating will be placed on the removable bottom of the ice-chamber, and on this grating the ice is intended to rest. The ice-chamber will not extend to the top of the drawer, but leaves a small space between it and the top of the case. The inner side f of the chamber should be slotted or formed of open work, to allow the ready passage of cold air out of the chamber into the drawers.

It will be perceived that said cold air must find an exit somewhere; for this purpose it will diffuse itself entirely throughout the drawers, and subject everything therein to its cooling influence, then pass into the space E, then up the space D, without again passing over the articles of food, and thus out into the atmosphere through pipes g, which communicate with the space D and the atmosphere.

The top drawer should possess some means of fastening, in order to prevent it from being drawn out before the pipes d e are uncoupled or disconnected. As soon as this is accomplished, and the fastenings relieved, the drawer is ready to be withdrawn.

The door of each drawer is first swung down, thereby exposing the interior of the drawers, which are then drawn directly forward out of the case, and full access is had to all parts of the drawer, either for the cleansing thereof or removal of the food therefrom.

The entire drawer can be removed, if desired. When all the drawers are removed, the walls of the case alone remain.

The refrigerator is then in a condition for cleansing purposes, repairs, or any purpose necessary or desirable.

It is not always necessary to withdraw the drawers, either partly or to their full extent, since access is had therein when the front door is swung open.

The drawers or inner walls may be lined, when desired, with any anti-corrosive metal, in the usual manner.

Having thus described my invention, what I claim as new, and desire to secure by Letters Patent, is—
In refrigerators, the construction of the sliding drawer-shelves E, with swinging doors C, and with a space, D, between their backs and the inner wall of the case, and the tubes g, communicating with the atmosphere, substantially as and for the purpose described.

To the above I have signed my name, this 22d day of April, 1869.
